US00D572136S

(12) **United States Design Patent**
Boni

(10) **Patent No.:** **US D572,136 S**
(45) **Date of Patent:** **** Jul. 1, 2008**

(54) **CONTAINER**

(76) Inventor: **Howard J. Boni**, 6209 E. 2nd St.,
Tucson, AZ (US) 85711

(**) Term: **14 Years**

(21) Appl. No.: **29/251,736**

(22) Filed: **Jan. 11, 2006**

(51) **LOC (8) Cl.** **09-01**

(52) **U.S. Cl.** **D9/503; D9/741**

(58) **Field of Classification Search** **D9/500,**

D9/502–505, 516, 523–524, 526, 529, 549–550,
D9/556–558, 655–656, 658–659, 737–738,
D9/741, 901–905; D24/121, 224; 215/379,
215/306; 220/660

See application file for complete search history.
